TO THE OLIVER TYPEWRITER COMPANY, OF CHICAGO, ILLINOIS, A CORPORATION
OF ILLINOIS.

BELL-RINGING MECHANISM FOR TYPE-WRITING MACHINES.

984,907

Specification of Letters Patent. Patented Feb. 21, 1911.

Application filed July 11, 1910. Serial No. 571,379.

To all whom it may concern:

Be it known that we, GEORGE J. GRIFFITHS and CHARLES RODERICK, citizens of the United States, and residents of Woodstock, in the county of McHenry and State of Illinois, have invented certain new and useful Improvements in Bell-Ringing Mechanism for Type-Writing Machines; and we do hereby declare that the following is a full, clear, and exact description thereof, reference being had to the accompanying drawings, and to the letters of reference marked thereon, which form a part of this specification.

15 This invention relates to improvements in typewriting machines, and particularly to certain novel features of construction of the bell-ringing mechanism which indicates when the end of the line is approached.

20 The invention consists of the matters hereinafter described and more particularly pointed out in the appended claims.

In the drawings:—Figure 1 is a top plan view of a typewriting machine with the 25 paper-carriage removed and also the type-carriers, the upright standards upon which said type-carriers are supported being shown in cross-section, as is also a part of the front bar of the paper-carriage. Fig. 2 is a partial vertical section through Fig. 1 on the line 2—2 thereof, with the bell-ringing hammer in that position which it occupies just 30 previous to striking. Fig. 3 is a partial vertical section through Fig. 1 on the line 3—3 thereof, showing the bell-ringing hammer after striking. Fig. 4 is a vertical section through Fig. 3 on the line 4—4 thereof. Fig. 5 is a perspective view of the standard 35 which carries the hammer. Fig. 6 is a perspective view of the hammer-actuating and controlling spring.

We have shown our invention in connection with a machine of the "Oliver" type, substantially such as is illustrated in Letters 45 Patent of the United States, No. 862,566, issued August 6th, 1907, to Theron L. Knapp and Clayton C. Harting, but it is to be understood that it may be applied to other machines of different types.

50 In the drawings,—1 indicates the base of the machine; 2, the shift-frame; 3, the vertical standards upon which the type-members are supported; and 4, the front bar of the typewriter carriage. The said front bar

4 is the front longitudinal frame member 55 of the carriage which constitutes the rack-bar thereof and on the front face of which are formed rack-teeth 6 (see Fig. 2) which are engaged by the devices for controlling the endwise movement of the carriage under the 60 action of its actuating spring.

7 is a depending flange formed on the longitudinal frame bar 4, and 8 is the right hand margin stop member which arrests the movement of the carriage when it has 65 reached its left-hand limit of movement. Said stop-member is provided with the usual stop lug 9.

10 is the bell supported on the machine base 1. 70

11 is a rock-shaft extending in a direction at right angles to the path of travel of the carriage and adapted to operate the bell ringing hammer 12 which is located adjacent the bell. Said rock shaft is mounted 75 in suitable bearing lugs 2^a on the shift-frame 2. Said rock-shaft projects forward of the front bar 4 of the paper-carriage and is there provided with a rigidly attached upper crank arm 13. 14 is a dog pivoted to the upper end of said crank arm and adapted to swing on an axis parallel to that of the rock shaft 11. Said dog is adapted to swing freely toward the right but is limited in its movement toward the left by a forwardly 80 projecting lug or heel 14^a which engages against the left-hand edge of the crank arm 13. Said dog projects up into the path of the stop lug 9 on the stop member 8. 85

The hammer 12 is made from a flat plate 90 and comprises a rounded head 12^a which is adapted to engage the bell, and a stem 12^b having a flat base 12^c. Said hammer is pivotally mounted on a standard 15 comprising an upright member 15^a and a slotted horizontal base 15^b. The pivotal point of the hammer is located near the base of its stem and to one side of its central longitudinal axis. 95

17 is a spring which controls the operation 100 of the hammer. Said spring has a lateral extension in the form of an elongated loop 17^a interposed between the base 15^b of the standard 15, said loop being of substantially the form and size of said base, and having 105 upstanding lugs 17^b which are adapted to engage against the margins of said base. Said spring and said hammer-standard are

secured to the machine base by a screw 18 which passes through the loop of the spring, and the slotted base of the standard. By this construction the hammer and its controlling spring may be adjusted, together, to properly position them with reference to the bell. The spring 17 consists of an upright operating member 17^a and a horizontal cushion member 17^b. The cushion member 17^b rests upon the machine base but is curved at its free end slightly upward and stands in position to be engaged by the hammer a little in advance of the engagement of the hammer with the bell, so that in the operation of ringing the bell this part of the spring is put under tension and will operate to immediately raise the hammer from the bell after the bell has been rung. This prevents the continued vibration of the hammer in contact with the bell after the bell has been struck. The operating member 17^a of the spring projects upward from the machine base into a position such that it engages the flat base 12^a of the hammer stem at a point above its pivotal connection with the supporting standard 15. This member of the spring is put under tension as the hammer is rotated to the left, as shown in Fig. 2, and when the hammer is released it causes said hammer to strike the bell. The rock shaft 11 is provided at its rear end with a crank arm 11^a carrying a crank pin 11^b which projects through a slot 12^a formed in the hammer.

The operation of the device is as follows: Consider the parts in that position which they occupy after the bell has been struck by the hammer, as illustrated in Fig. 3, when the hammer is held by the member 17^a of the operating spring away from the bell. As the carriage advances toward the left, thereby bringing the writing on the sheet toward the right hand margin thereof (see Fig. 2), the stop lug 9 of the stop member 8 strikes the dog 14 and rotates it toward the left. As soon as the lug or heel 14^a of said dog strikes the crank arm 13, said crank arm is rotated toward the left and with it, the rock-shaft 11, the crank arm 11^a and crank pin 11^b. This movement of the crank pin raises the hammer against the action of the operating member 17^a of the spring, thereby putting said member of the spring under tension. Said movement is continued until the stop lug 9 slides off the end of the dog 14, when the crank-arm 13 is released, and with it the hammer, which is then caused to forcibly strike the bell under the action of the member 17^a of the spring. Just before the hammer strikes the bell, its rounded lower face engages the cushion member 17^b of the spring, which is thus under tension when the bell is finally struck, and returns the hammer to a position slightly above the bell, thereby prevent-

ing the continued vibration of the hammer with the bell after the latter has been struck.

We claim as our invention:—

1. In a typewriting machine, in combination with the machine base, the paper-carriage, a bell, a swinging hammer, and means actuated by the carriage for swinging said hammer away from said bell and for releasing it at a predetermined point, a standard 70 adapted to support said hammer, a spring for operating and controlling said hammer, means for adjustably securing said standard and said spring to the machine base, said spring consisting of a hammer-operating member adapted to be put under tension when said hammer is swung away from said bell, and of a cushion member adapted to be struck by said hammer previously to the engagement of said hammer with the bell, and 80 to remove said hammer from contact with the bell after the bell has been struck.

2. In a typewriting machine, in combination with the machine frame, the paper-carriage, a bell secured to the machine frame, a swinging hammer, and means actuated by the carriage for swinging said hammer away from said bell and for releasing it at a predetermined point, a standard for said hammer embracing an upright member to 95 which said hammer is pivotally connected and a slotted base, a spring for controlling and actuating said hammer comprising a flat loop extension lying beneath said standard base and having upright lugs engaging 100 the marginal edges of said standard base, an operating member adapted to be put under tension when said hammer is swung away from said bell, and a cushioning member adapted to be struck by said hammer previously to the engagement of said hammer with the bell and to remove said hammer from contact with the bell after the bell has been struck, and a screw adjustably securing 105 said standard base and said loop extension 110 of the spring to the machine frame.

3. In a typewriting machine, a bell-ring- 115 ing mechanism including a swinging ham- mer, said hammer comprising a head and a stem having a flat base, means for pivotally mounting said hammer, and a controlling and actuating spring for said hammer comprising an upright member engaging the flat base of said stem and a cushion member adapted to be struck by the head of said 120 hammer previously to its engagement with the bell and to remove said hammer from contact with the bell after said bell has been struck.

4. In a typewriting machine, in combina- 125 tion with the machine frame, the paper-car- riage, a bell secured to the machine frame, a swinging hammer, and means actuated by the carriage for swinging said hammer away from said bell and for releasing it at a pre- 130

determined point, a standard for said hammer embracing an upright member to which said hammer is pivotally connected and also a base, a spring for con. rolling and actuating said hammer comprising a laterally extended base, an operating member adapted to be put under tension when said hammer is swung away from the bell, and a cushioning member adapted to be struck by said hammer previously to the engagement of said hammer with the bell and to remove the hammer from contact with the bell after the bell has been struck, rigid parts carried by

one of said bases adapted to engage with the other base and means for securing said bases to the machine frame.

In testimony, that we claim the foregoing as our invention we affix our signatures in the presence of two witnesses, this 30th day of June A. D. 1910.

GEORGE J. GRIFFITHS.
CHARLES RODERICK.
